UNITED STATES PATENT OFFICE.

BENJAMIN L. DRESSER, OF UXBRIDGE, MASSACHUSETTS.

TROLLEY-HARP.

No. 876,700.

Specification of Letters Patent.

Patented Jan. 14, 1908.

Application filed March 19, 1907. Serial No. 363,182.

To all whom it may concern:

Be it known that I, BENJAMIN L. DRESSER, a citizen of the United States, residing at Uxbridge, in the county of Worcester and State of Massachusetts, have invented certain new and useful Improvements in Trolley-Harps, of which the following is a specification.

This invention contemplates certain new and useful improvements in trolley-poles and harps, and the invention has for its object an improved detachable connection between a trolley-pole and its harp whereby the latter may be quickly attached to or detached from the former.

The invention also embodies improvements relating particularly to the trolley-harp for which Letters Patent of the United States were issued to me August 28, 1906,

No. 829,390.

For a full description of the invention and the merits thereof and also to acquire a knowledge of the details of construction of the means for effecting the result, reference is to be had to the following description and accompanying drawings, in which:

Corresponding and like parts are referred to in the following description and indicated in all the views of the drawings by the same reference characters.

Figure 1 of the drawings represents a vertical section of the device. Figs. 2, 3 and 4 illustrate the means for attaching the trolley head to the pole.

Referring to the drawings, the numeral 1 designates a trolley-pole which is provided at one end with a reduced shank 2 and 4 designates a harp which embodies complementary plates or members clamped together in spaced relation so as to receive the shank 2 between them and adapted to extend in a divergent manner beyond the said shank so as to constitute the yoke in which the trolley wheel 5 is journaled. The spindle 6 of the trolley wheel is shown mounted in the outer ends of the harp, and a pair of outside springs 7 are apertured at their outer ends to receive the squared ends of the spindle and are adapted to hold the said spindle in place as against longitudinal displacement.

8 designates a pair of inside leaf springs that are located on opposite sides of the trolley wheel 5 and are formed at their outer ends with apertures to receive the spindles 6. 55 The above described construction is set forth

in detail in the schedule of my said Letters Patent, to which reference may be had.

My present invention comprehends particularly the means for attaching the harp to the pole.

As illustrated in the drawing, the reduced shank 2 of the pole is provided at its outer end with oppositely facing and oppositely positioned spring hooks 9, preferably set in the recesses of the shank with normal tension exerted to swing the hooked ends 10 outwardly. In the practical operation of attaching the harp to the pole, it is only necessary to slip the harp over the shank 2 which will effect the contraction of the hooks 9 or force their outer hooked ends 10 toward each other and hold them in contracted relation until the harp shall have been slipped over the shank to its limit, whereupon the said hooks are permitted to spring outwardly and engage with the outwardly facing shoulders 11 of the inner sides of the harp members so as to effect a secure connection between the harp and pole. In this relation of the parts the lower end of the harp preferably abuts against the shoulder formed by the reduced shank 2.

It is to be understood that the shank 2 and the socket that is formed within the harp to receive it, may be made of any cross sectional outline either round or rectangular and that the invention is applicable to any ordinary form of harp as well as the patented harp referred to. For instance as shown in Fig. 3, 4^a designates an ordinary harp with a round bore or socket and it will be seen by reference to said figure that my improved pole with its spring hooks 9 may be inserted into said socket so as to permit the hooks to spring outwardly at the fork end of the harp and thereby securely hold the harp to the pole.

As illustrated in Fig. 4 the ordinary type of harp 4^b may be formed with a square socket or bore to receive the square end of the shank of the pole.

To detach the harp from the pole it is only necessary for the trainman to grasp the hooked ends 10 between his thumb and finger and press them inwardly which will result in releasing the hooks from engagement with the harp and permit the latter to be slipped off the pole.

From the foregoing description in connection with the accompanying drawing, it

will be seen that I have provided a very simple and durable construction of detachable trolley harp by which the operation of attaching and detaching the hoop to and 5 from the pole may be accomplished expeditiously.

Having thus described the invention, what is claimed as new is:

1. In combination, a trolley harp provided with a socket extending therethrough and with outwardly facing shoulders communicating with said socket, of a pole adapted to be inserted within said socket and outwardly facing spring hooks secured to the 10 end of said pole and arranged to slip through said socket and spring outwardly into engagement with said shoulders.
- 15 2. In combination with a trolley harp pro-

vided with a socket extending therethrough and with outwardly facing shoulders communicating with said socket, of a trolley pole provided with a reduced shank adapted to be slipped into said socket and with oppositely facing recesses at the extremity of said shank and spring hooks secured in said recesses and facing away from each other whereby when the shank is slipped into the socket the said hooks will spring outwardly into engagement with the shoulders and fasten the harp to the pole.

In testimony whereof I affix my signature in presence of two witnesses.

BENJAMIN L. DRESSER.
